Assignor to

The Lowell Manufacturing Company,
Letters Patent No. 1647 dated Aug. 12, 1862.

The schedule referred to in these Letters Patent and making part of the same,

To all, whom it may concern:

Be it known that I, Clemir J. Ney, of Lowell, in the County of Middlesex and State of Massachusetts, have originated and designed a new pattern for carpets or other fabrics, of which the following is a full, clear and exact description, reference being had to the accompanying drawings, making part of this specification.

In this pattern are series of octagonal figures in the interiors of which are small blocks and dotted lines.

Lying between the two series of octagonal figures, are oblong figures composed of lines running parallel with each other and joined to the solid outline of the figures. The remaining figures are solid square blocks connected with the oblong figures, before mentioned, by dotted lines.

The colors employed for the different portions of the design may be varied to suit the taste and wish of the manufacturer.

Claim.
